(74) Attorney, Agent, or Firm — Merchant & Gould P.C.

(57) **CLAIM**

An ornamental design for a knob as shown and described.

DESCRIPTION

FIG. 1 is a top perspective view of an exemplary knob according to a new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof; and,
FIG. 9 is a section view taken along the reference line 9-9 of FIG. 6.

The portions depicted in broken lines form no part of the claimed design.

1 Claim, 9 Drawing Sheets
